UNITED STATES PATENT OFFICE.

WILLIAM D. LINSCOTT, OF PIEDMONT, SOUTH DAKOTA.

CATTLE-GUARD.

No. 810,064.

Specification of Letters Patent.

Patented Jan. 16, 1906.

Application filed July 3, 1905. Serial No. 268,208.

To all whom it may concern:

Be it known that I, WILLIAM D. LINSCOTT, a citizen of the United States, residing at Piedmont, in the county of Meade and State 5 of South Dakota, have invented certain new and useful Improvements in Cattle-Guards, of which the following is a specification.

This invention embodies improvements in that type of cattle-guards particularly designed to be placed at the crossing of a railroad-track or used in a similar capacity to prevent cattle from going onto the track.

The invention includes generally a movable platform across the track and a gate or gates operably connected therewith so as to be actuated and raised should the cattle step upon the movable platform in attempting to wander on the track.

For a full description of the invention and 20 the merits thereof and also to acquire a knowledge of the details of construction of the means for effecting the result reference is to be had to the following description and accompanying drawings, in which—

25 Figure 1 is a view showing a cattle-guard embodying the invention, the gates being disposed in their normal position or lowered to lie out of the path of movement of the rolling-stock passing over the track. Fig. 2 is a perspective view, the movable platform of the guard being depressed or lowered so as to raise the gates into operative position. Fig. 3 is a top plan view of a cattle-guard such as embodied in this invention. Fig. 4 is a vertical longitudinal sectional view.

30 Corresponding and like parts are referred to in the following description and indicated in all the views of the drawings by the same reference characters.

40 In one of the preferred uses of the invention two cattle-guards such as embodied in the invention are preferably located at opposite sides of a railroad-crossing, leaving sufficient room for wagons to cross.

45 Specifically describing the construction of the guard, the numeral 1 designates a movable platform composed of a number of boards or planks or constructed in any suitable way, said platform being pivotally supported at one side, as shown at 2, by being secured to the cross-ties of the track or in any other way suitable for the purposes. The side of the platform 1 opposite that pivotally supported at 2 is pivotally connected with

50 the sides of a gate 3, said gate 3 being adapted to assume a horizontal position between

the rails of the track, as shown most clearly in the drawings. The sides of the gate 3, which gate may be made of any suitable construction within the contemplation of the invention, are pivotally mounted upon a rock-shaft 4, the latter having cranks 5 at its ends, said cranks being pivotally connected with suitable supports in the length of the track 6. The pivotal connection between the platform 1 and the gate 3 (indicated at 7) admits of operation of the gate in such a manner that when the platform 1 is forced downwardly or depressed the gate 3, normally resting flat upon the ties of the track, will be elevated 65 and will prevent the animal actuating the platform 1 from going onto the track in an obvious manner. In the drawings auxiliary gates 3^a, of virtually the same construction as the gate 3, but narrower, will be arranged 70 at opposite sides of the track 6, being mounted upon the shaft 4 in exactly the same way as described with reference to the gate 3. The gates 3 and 3^a constitute a single guard when operably connected with the platform 75 1, as hereinbefore set forth.

It is designed that the several gates 3 and 3^a shall be provided with barbed wires or the like, so as to effectively prevent the cattle from trying to pass the gates after the latter 80 have been raised.

The rolling-stock may of course pass over the guard under normal conditions, as the gate 3 and 3^a normally assume horizontal positions below the level of the rails of the track 6. 90

It will be seen that the construction of the guard hereinbefore set forth is very simple and practical and may be very cheaply made, being extremely effective in accomplishing the desired results.

Having thus described the invention, what is claimed as new is—

In a cattle-guard, the combination of a movable platform, a gate normally in horizontal position and embodying sides pivotally connected at one end with the platform, and a rock-shaft having pivotal connection with the sides of the gate between the ends of the latter, said rock-shaft having end cranks pivotally mounted in suitable supports. 105

In testimony whereof I affix my signature in presence of two witnesses.

WILLIAM D. LINSCOTT. [L. S.]
